UNITED STATES PATENT OFFICE.

ALOIS ZWIERZINA, OF DETROIT, MICHIGAN, ASSIGNOR TO JOSEPH N. SMITH & CO., OF DETROIT, MICHIGAN, A CORPORATION OF MICHIGAN.

ANTIRATTLING DOOR-LATCH.

1,325,970.

Specification of Letters Patent. Patented Dec. 23, 1919.

Application filed June 27, 1918. Serial No. 242,269.

To all whom it may concern:

Be it known that I, ALOIS ZWIERZINA, a subject of the Emperor of Germany, residing at Detroit, county of Wayne, State of Michigan, have invented a certain new and useful Improvement in Antirattling Door-Latches, and declare the following to be a full, clear, and exact description of the same, such as will enable others skilled in the art 10 to which it pertains to make and use the same, reference being had to the accompanying drawings, which form a part of this specification.

This invention relates to door latches for 15 use particularly with doors of automobile bodies and its object is to provide a simple and efficient device for automatically preventing a rattling of the door when in closed position. An additional object is to provide 20 a spring pressed latch bolt having a part adapted to assume a wedging relation with the striker plate and thus hold the latch member from rattling.

Heretofore with the usual bumpers of 25 rubber and the like used for the purpose of preventing a rattling of the door latch, the said bumpers become worn and ineffective for the purpose, and an additional object of this invention is to provide an anti-rattling device for door latches positioned on 30 or controlled by the bolt member adapted to automatically wedge the bolt in the striker plate and adapted to automatically take up wear. These objects and the several novel 35 features of the invention in its preferred form are hereinafter more fully described and claimed and shown in the accompanying drawings in which—

Figure 1 is a perspective view of a door 40 latch embodying my invention.

Fig. 2 is a longitudinal section thereof taken on line $x-x$ of Fig. 1, showing the latch bolt in position in the striker plate.

Fig. 3 is a face view of the striker plate 45 showing the latch bolt in position.

The case for the latch may be of any approved form or construction, the case shown in the drawings consisting of an L-shaped plate 1, the short leg of which is provided 50 with an aperture through which projects the end 2 of the latch bolt 3. This bolt is slideable in the case between the member 1 thereof and a second member 4 secured thereto. The bolt body may be of any approved type 55 preferably one in which a lug 5 is provided

extending into the slot 6 in the casing 1 as shown in Fig. 1. The casing 4 may be provided with an aperture 5^a allowing the head of the bolt 2 to be withdrawn from the aperture in the short leg of the case 1, as will be 60 understood from Fig. 2. This latch bolt may be operated by any approved means, the operating lever 6 here shown being of ordinary type pivoted by means of a screw 7 to the case 1. This lever, as will be understood from Fig. 2, has the back edge thereof in engagement with a lug 8 at the rear end of the bolt 3 so that by moving the lever backward the bolt may be withdrawn 65 against the tension of the usual coiled spring 70 9 mounted in the case on a pin 10 and having an end in engagement with the latch member 3. This construction is well known and in fact any character of spring may be utilized tending to force the end 2 of the 75 latch member through the aperture in the case.

The face of the bolt end 2 is curved as shown in the drawing, so that on closing the door said latch will be retracted by engagement of this rounded face of the bolt end with the striker plate 11, which is to be understood as being secured to the door post. The striker plate 11 is provided with an aperture 12 for the bolt end and is also 80 provided with a slot like aperture 13 opening into the aperture 12 in the plate as shown in Fig. 3. The end of the latch member is also provided, preferably on the upper side, with a wedge member 14 which is 85 adapted to engage in the slot 13 of the striker plate.

It is to be noted that the said end 2 of the bolt is somewhat less in width than the aperture 12 in the striker plate allowing it 95 to freely enter the aperture on the closing of the door. The wedge member 14 however, is somewhat wider at the base than the width of the aperture 13 in which it is to engage. Therefore, on the door being 100 closed and the bolt end 2 and wedge portion 14 thereon introduced into the aperture 12 and 13, the wedge member 14 will wedge tightly in the aperture 13 by action of the bolt spring and the arrangement of parts is 105 such that the portion 14 seats in the aperture 13 prior to the latch being forced forward to its otherwise fullest possible extent by action of the spring 9. This allows for considerable wear so that, as the aperture 13 110

and wedge portion 14 becomes worn, the latch member is forced forward to wedging position. This wedging relationship of part 14 in the slot or aperture 13 prevents the 5 latch from rattling in the striker plate and the desired object of this invention is secured.

As is shown in Fig. 2 the striker plate when the latch member is in registration 10 therewith is spaced slightly from the face of the case 1 to allow free movement of the door relative thereto and it is to be understood that the striker plate is held in such relationship by being secured to the door 15 post.

From the foregoing description it is evident that by this arrangement of a wedging member of the character described preferably formed on or secured to the latch member, an automatically operating anti-rattling 20 door latch is provided that is extremely simple in form and inexpensive in construction and automatically takes up wear.

Having thus briefly described my invention, what I claim is—

1. In a door latch, a spring-pressed latch bolt, means for operating the same, a wedge member formed integrally with the bolt, and a striker plate having an aperture for 30 the bolt and wedge member in which the said wedge member assumes a wedging relation by action of the bolt spring.

2. In a door latch, a spring pressed bolt member, a striker plate therefor apertured 35 to receive the bolt, said bolt having an end curved on one side to operate the bolt by contact with the striker plate and having a portion at said end provided with flat faces positioned at an angle one to the other, the 40 striker plate having an aperture for said portion, the width of the aperture being less than the width of the said portion near the wider end.

3. In a door latch, a spring pressed latch bolt, a striker plate apertured to receive the 45 bolt, the bolt end having a curved face on one side and a wedge shaped portion formed on one edge thereof, the striker plate having an aperture coextensive with the bolt aperture in which the wedge shaped portion 50 has a wedging engagement by action of the bolt spring.

4. In a door latch, a spring pressed latch bolt, having a curved face and a flat face in angular relation, a wedge like member having oppositely inclined flat faces positioned on the upper edge of the bolt end, one face thereof being coextensive with the flat face of the bolt, and a striker plate for the said bolt having an aperture shaped to receive the 60 bolt end and wedge member, the wedge member seating in the portion of the aperture provided therefor.

5. In a door latch, a spring-pressed latch bolt provided with a wedge shaped portion 65 formed integrally on one side thereof, and a striker plate having an aperture for the bolt and wedge member and in which the said wedge shaped portion may seat by action of the bolt spring.

6. In a door latch, a spring pressed latch bolt provided with a curved and flat face in angular relation, and a portion having inclined flat faces one face of which is coextensive with the flat face of the bolt end, 75 the angle therebetween being less than the angle between the curved and flat faces of the bolt, and a striker plate having an aperture for the said bolt slightly larger than the bolt end and an aperture for the said 80 flat faced portion in which said portion may seat.

In testimony whereof, I sign this specification.

ALOIS ZWIERZINA.
